CHAIN-STITCH SEWING MACHINE

Albert H. De Voe, Westfield, N. J., assignor to
The Singer Manufacturing Company, Elizabeth,
N. J., a corporation of New Jersey

Application April 15, 1932. Serial No. 605,407

42 Claims. (Cl. 112—81)

This invention relates to improvements in stitch-forming mechanisms for sewing machines generally, and is particularly adapted for effecting the production of ornamental open-work 5 seams, such as hemstitching and the like.

The present invention has for an object to provide an improved looper mechanism for co-operation with the needle or needles of a chain-stitch sewing machine, and more specifically for 10 cooperation with an endwise reciprocatory and laterally vibratory needle, or needles.

Another object of this invention is to provide 15 a commercially practical chain-stitch hemstitching machine. Other and more specific objects of the invention will be apparent from the following description and claims.

In a prior effort to provide a chain-stitch hemstitching machine, represented by the U. S. Patent to L. Onderdonk, No. 962,973, June 28, 1910, 20 the needles were offset in the line of seam formation to accommodate the cooperating thread-carrying loopers, thereby presenting the undesirable condition of the needles simultaneously 25 working at opposite sides of successive piercer openings, instead of both sides of the same piercer opening, with the attendant uncertainty 30 of clean penetration of the partially worked piercer opening by the finishing needle and piercer, and particularly for different adjustments of the amplitude of advance of the work by the feeding mechanism. The prior construction furthermore presents the inherent defects of 35 improperly starting and finishing a hemstitch seam and of being unadapted for effecting the production of curved or sharply angled hemstitched seams.

The present improvement is designed to overcome the inherent defects in the prior machine by the provision of stitch-forming mechanism 40 including a chain-stitch looper mechanism capable of cooperation with a pair of needles which are disposed abreast with respect to the direction of feed at opposite sides of a piercer.

The invention consists in the devices, combinations and arrangements of parts hereinafter described in connection with the accompanying drawings, and pointed out in the appended claims.

In the drawings, Fig. 1 represents a vertical, 45 longitudinal section of a hemstitching machine containing a preferred embodiment of the present invention. Fig. 2 represents a rear side elevation of the machine. Fig. 3 is a front end elevation of the bracket-arm head of the machine with the face-plate removed, and showing the 50 bed-plate in transverse section. Fig. 4 is a detail

view in top plan of the needle-thread take-up members, with the needle and piercer-bars in section. Fig. 5 is a section of the machine bracket-arm substantially on the line 5—5 of Fig. 2. Fig. 6 is a sectional view of the slack-thread controllers substantially on the line 6—6 of Fig. 3, and Fig. 7 a section thereof on the line 7—7 of Fig. 2. Fig. 8 is a bottom plan view of the machine. Fig. 9 is a sectional view through the bed-plate substantially on the line 7—7 of Fig. 1. Figs. 10, 11, and 12 are detail views of the looper actuating cranks. Fig. 13 is a sectional view of the bracket-arm standard substantially on the line 13—13 of Fig. 1. Fig. 14 represents a perspective view of the loop-detainers and Fig. 15 a similar view of the needle-guide and carrier for the loop-detainers. Fig. 16 is a perspective view of the detainer carrying rock-shaft. Fig. 17 is a top-plan view of the cloth- or bed-plate, with the bed-slides and throat-plate removed and with the bracket-arm standard in horizontal section. Fig. 18 is a substantially vertical section of one of the looper-carriers. Fig. 19 is a vertical section of the looper-supporting bracket substantially on the longitudinal axis of the loop-detainer rock-shaft. Fig. 20 represents perspective views of the presser-foot parts illustrated in detached relationship. Fig. 21 represents a top-plan view of a looper mechanism, including both thread-carrying and non-thread-carrying loopers in their loop-seizing positions with respect to the two needles shown in section. Fig. 22 represents an elevation of the left hand or non-thread-carrying looper and of the thread-detainer as viewed from the left in the position indicated in Fig. 21. Fig. 23 represents an elevation of the right hand or thread-carrying looper and of the thread-detainer as viewed from the right in Fig. 21. Fig. 24 is a view similar to Fig. 21 and in a succeeding position of the looper mechanism in which the loop-detainer fangs are beginning to enter the respective thread-loops and the loopers have been moved sideways to begin their retracting movements. Figs. 25 and 26 are respectively left hand and right hand views in elevation of the looper mechanism parts in positions thereof corresponding to Fig. 24. Fig. 27 is a top-plan view of the looper mechanism in a position thereof succeeding that illustrated in Fig. 24 and at about the mid position of advancing movement of the loop-detainer. Fig. 28 is a left hand view in elevation of the parts in the positions thereof corresponding to Fig. 27. Fig. 29 is a rear side elevation of the looper mechanism illustrated in Fig. 27. Fig. 30 is a top-plan view of the looper mechanism in

the loop-shedding positions of the loopers. Figs. 31 and 32 are respectively left hand and right hand views in elevation of the parts in positions thereof corresponding to Fig. 30. Fig. 33 is a 5 top-plan view of the loopers and loop-detainers in substantially the retracted positions of the loopers, with the needles beginning to enter the thread-loops spread by the detainers. Figs. 34 and 35 are respectively left hand and right hand 10 views in elevation of the looper mechanism parts in positions thereof corresponding to Fig. 33. Fig. 36 is a rear side elevation of the thread-detainers, with the needles entering the thread-loops upon the detainers. Fig. 37 is a top-plan 15 view of the throat-plate and of the feed-dog, with the latter in its rising position. Fig. 38 represents perspective views of the needle-thread nipper releasing mechanism, with parts thereof in detached relationship. Fig. 39 is a top-plan view 20 of a modified looper arrangement according to which two non-thread carrying loopers are employed. Fig. 40 represents another modification in which two thread-carrying loopers are shown as cooperating with the thread-detainers.

25 *Needle-actuating mechanism*

Referring to the drawings, the present improvements have been embodied in a hemstitching machine having needle-vibrating mechanism 30 of the general character disclosed in the U. S. Patent to G. M. Eames et al., No. 1,721,072, July 16, 1929. The machine has the usual framework including a bed- or cloth-plate 1, from which rises a hollow standard 2 of an overhanging 35 bracket-arm 3 terminating in a head 4. Journaled in suitable bearings provided in the overhanging bracket-arm is a rotary main-shaft 5, carrying at one end a belt-pulley 6 and at its opposite end a crank-disk 7, having a crank- 40 pin 8 connected by a specially constructed link 9 with a pin projecting laterally from a collar 10 suitably clamped upon a needle-bar 11.

The needle-bar 11 is journaled for vertical reciprocation in bearings provided in the head 4 45 and carries at its lower end a supporting plate 12 pivotally sustaining a pair of needle-carriers 13 and 14 in which the needles 15 and 16 are suitably secured. Fixed upon the needle-carriers 13, 14, are the vertically directed guide-rods 17 50 and 18 having sliding swivel connections with crank-arms 19 and 20 clamped upon the front ends of horizontally disposed rock-shafts 21 and 22 suitably journaled in the lower portion of the bracket-arm head 4. Secured upon the rearward 55 ends of the rock-shafts 21, 22 are oppositely directed crank-arms 23 and 24 connected by links 25 and 26 with corresponding arms of bell-crank levers 27 and 28 fulcrumed adjacent to each other upon the rearward side of the bracket-arm 60 head 4. The other arms of said bell-crank levers are pivotally connected to the forward ends of horizontally disposed pitman-rods 29 and 30 of which the opposite ends are respectively pivoted to blocks 31 and 32 adjustably secured in adjacent guideways provided in a vibratory arm 33.

The arm 33 has an elongated hub 34 loosely journaled upon a rock-shaft 35 disposed transversely of and below the main-shaft 5, said rock-shaft being journaled in suitable bearings provided in the bracket-arm standard 2. The vibratory arm 33 carries a roller-stud 36 entering a cam-groove 37 provided in the periphery of a needle-vibrating cam 38 suitably secured upon the hub-sleeve 39 of a spur-gear 40 rotatably 70 journaled upon a stub-shaft 41 suitably fixed in

the bracket arm 3 below and parallel with the main-shaft 5. The spur-gear 40 meshes with a pinion 42 of one third the size of the spur-gear and is suitably secured upon the main-shaft 5.

80 *Piercer mechanism*

The present machine also includes a piercer mechanism commercially well known in hemstitching machines. This mechanism includes a piercer 43 disposed between and recessed at opposite sides thereof to receive the needles, said piercer having a rearwardly offset shank secured in a piercer-holder 44 carried by the lower end of a piercer-bar 45 journaled for vertically reciprocatory movements in the bracket-arm head 4. Secured upon the piercer-bar 45 is a collar 46 to which is pivotally connected a crank-arm 47 of a rock-shaft 48 journaled in bushings 49 and 50 suitably fixed in spaced bearing lugs 51 and 52 at the rear side of the machine bracket-arm. Fixedly clamped upon the rock-shaft 48 is a crank-arm 53 (Fig. 5) pivotally connected to one end of a pitman 54 of which the opposite end is provided with a strap embracing an eccentric 55 upon the main-shaft 5. From this it will be understood that the piercer reciprocates once for each needle reciprocation, the relative timing being such that the piercer both descends and rises in advance of the corresponding movements of the needles. If desired, there may also be employed an auxiliary piercer 56 disposed in advance of the piercer 43 and carried by an auxiliary holder 57 secured upon a supporting bar 58 extending from the needle-carrier plate 12.

105 59 *Feeding mechanism*

The work-feeding mechanism employed is of the well known type in which the work is advanced once only during the formation of three successive stitches. A lower four-motion feed-dog 59 is 115 carried by a feed-bar 60 of which one end is pivotally connected with a crank-yoke 61 of a feed rock shaft 62 journaled in suitable bearings at the front under side of the bed plate 1. The forked opposite end of the feed-bar 60 is operatively connected to a crank-arm 63 of a feed-lift rock-shaft 64 journaled in suitable bearings at the rear under side of the bed-plate 1. The feed rock-shaft 62 carries a crank-arm 65 operatively connected to the lower end of a link 66 120 extending upwardly through a slot 67 in the bed-plate 1, the upper end of said link being adjustably secured upon a segment-lever 68 disposed outside of the bracket-arm. The segment-lever 68 is secured upon a fulcrum-shaft 69, disposed parallel with the main-shaft 5 and suitably journaled in the bracket-arm standard 2. Carried by the segment-lever 68 is a roller-stud 70 entering a cam-groove 71 formed in the side face of a feed-cam 72, suitably secured upon the hub-sleeve 39 of the spur-gear 40 and disposed adjacent to the needle-vibrating cam 38 within the bracket-arm. From the foregoing it will be understood that the feed-cam 72 rotates once only for three rotations of the main-shaft, the cam-groove 71 being so formed as to impart a work-advancing impulse to the feed-dog 59, while the needles are out of the work, and a retarded return movement during the formation of three successive stitches.

130 135 140 Clamped upon the feed-lift rock-shaft 64 is a crank-arm 73 connected by a link 74, within the bracket-arm standard 2, to a rock-arm 75 pivotally mounted upon the fulcrum-shaft 69. The rock-arm 75 carries a roller-stud 76 entering a feed- 145

lift cam-groove 77 in the side face of the spur-gear 40. In the present case, the cam-groove 77 is so formed and its rotation so timed with respect to the work-advancing movements of the feed-dog 59 that the latter after a forward work-advancing movement thereof is lowered during the succeeding descending movement of the needles, remains substantially stationary while the needles are in the work, returns slowly during the two succeeding needle reciprocations and rises with the needles during the third reciprocation of the latter.

The feed-dog 59 operates in parallel feed-slots provided in a throat-plate 78 suitably secured upon the cloth-plate 1, said throat-plate having an auxiliary-piercer aperture 80 in advance of a piercer- and needle-slot 81 extending transverse to the direction of feed. Opening into the rearward edge of said slot 81 is a pair of inner feed-slots 82 disposed between the outer feed-slots 83 at opposite sides of the needle-slot 81. The forward teeth of the feed-dog 59 operating in the feed-slots 82 rise within the needle-slot 81 and thereby serve to lift out of said needle-slot any portion of the work which may be forced thereinto by the needles and piercer. When the feed-dog moves forward to advance the work, the front ends of the feed-slots 82 are left open and thereby serve to provide the usual thread-loop clearance desirable in the formation of chain-stitches. The retarded return movement of the feed-dog leaves the slots open the requisite length of time for forming the succeeding stitches of a hem-stitch figure.

35 Presser-foot

Opposed to the feed-dog 59 is a presser-foot having a shank 84 secured upon the lower end of the usual spring-depressed presser-bar 85 journaled for vertical endwise movements in suitable bearings provided in the bracket-arm head 4. Referring more particularly to Figs. 3 and 20 of the drawings, the presser-foot shank 84 has a foot-plate supporting bracket 86 recessed in its under face to provide for vertically yielding movements of three spring tongues 87, 88, 89 formed adjacent each other in a flat spring-plate 90 secured by screws, as 91, to the under face of a shouldered ledge 92 to project forwardly from said ledge. Secured to the forward end of the spring-tongue 87, by screws, as 93, is a foot-plate 94 having upon its upper face and substantially midway between the ends thereof a spacing block 95 to receive the screws 93. The foot-plate 94 overlies one of the feed-slots 83 of the throat-plate and is provided with a piercer-aperture 96 in vertical alinement with the throat-plate piercer-aperture 80. Directly rearward of the piercer-aperture 96, the foot-plate 94 is provided with a needle and piercer-slot 97 which is left open at its rearward end by cutting away the heel of said foot-plate to receive a chaining-off or seam-engaging foot-plate 98. The upper face of the foot-plate 98 has a spacing-block 99 at its forward end to receive screws by means of which said foot-plate is secured to the forward end of the spring-tongue 88. Secured in like manner to the forward end of the spring-tongue 89 is a spacing block 100 upon the upper face and intermediate the ends of a foot-plate 101 disposed closely adjacent to the foot-plates 94 and 98.

By supporting the foot-plates 94 and 101 intermediate the ends thereof by the spring-tongues described, said foot-plates are capable of yielding and rocking movements independently of

each other to accommodate variations in thicknesses of work. The chaining-off foot-plate is likewise free to yield independently of the other foot-plates. In order to properly distribute to the several foot-plates the spring pressure exerted upon the presser-bar, there is provided a substantially horizontally disposed compensating plate 102 having triangularly-arranged pointed nubs 103, 104 and 105 on its under face, each bearing upon one of the spring-tongues. The nubs 103 and 104 bear upon the spring-tongues 87 and 89 at points close to the free ends of said tongues, while the third nub 105 bears upon the tongue 88 approximately midway between the ends thereof, whereby the chaining-off foot is under slightly less pressure than the other foot-plates. In order to transmit the pressure of the presser-bar to the foot-plates and to provide for universal rocking movements of the compensating-plate 102, a conically pointed screw 86' is vertically threaded into the shank-bracket 86 of the presser-foot, with the pointed end of the screw projecting below said bracket to freely enter a rounded depression 102' provided in the upper face of the plate 102 substantially centrally of the triangle formed by the plate nubs. The screw 86' is adjustably secured by a suitable nut in a position such that, when the presser-foot is raised, the compensating plate is confined by the point of the screw against edgewise movement, but is free to rock independently of the foot-plates. However, in the lowered position of the presser-foot with the usual spring pressure applied to the presser-bar, the plate 102 is free to rock conformably with vertically yielding movements of the individual foot-plates, and to this end the under face of the shank-bracket 86 is suitably recessed to afford the necessary clearance for the compensating-plate.

110 Looper mechanism

Cooperating with the needles in the formation of chain-stitches is a looper mechanism including a pair of loopers adapted to seize the needle-thread loops, either or both of which loopers may be of the threaded or non-threaded types, dependent upon whether it is desired to effect the production of double-thread or single-thread chain-stitches. With the exception of the modifications represented by Figs. 39 and 40, the machine illustrated in the accompanying drawings has an eye-pointed looper 106 for cooperation with the needle 16 in the formation of double-thread chain-stitches, and a hook-pointed looper 107 for cooperation with the needle 15 in the formation of single-thread chain-stitches, said looper 107 having a loop-detaining spur 107' adjacent to its point. It is to be understood that the primary purpose of mainly illustrating both types of loopers is in the interest of obtaining a better understanding of the stitch-forming operation of the respective loopers.

The looper 106 has a blade provided with the usual thread-eye near its point and an additional thread-aperture at its heel where said blade terminates in a laterally offset shank detachably secured in a horizontally-disposed socketed looper-carrying arm 110. The arm 110 is adjustably clamped upon the reduced upper end of a vertically disposed looper-carrying rock-shaft 112, which is journaled for oscillatory movements about its longitudinal axis in a vertically apertured rocking sleeve 113 provided intermediate its ends with a boss 114 apertured to receive a horizontally disposed fulcrum-pin 115.

suitably secured in said boss. The fulcrum-pin 115 is pivotally mounted in spaced bearing apertures of a looper-bracket 116 secured, for adjustment crosswise of the line of seam formation, upon a shelf 117 integral with the bed-plate 1.

Extending laterally from the lower end of the rock-shaft 112 is a crank-arm 118 in the free end of which is secured the threaded stem 119 of a ball 120 journaled in a ball-socket carrier-plate 121 detachably secured upon one member of a split sleeve 122 embracing an inclined shaft-crank 123 (Figs. 10 and 11). The shaft-crank 123 terminates at one end in a sleeve-confining head 124 and at its opposite end in a crank-dividing head 125 which, in the present case, is integral with one end of another shaft-crank 126 inclined oppositely to the shaft-crank 123, the other end of said shaft-crank 126 terminating in a sleeve-confining head 127. The crank-heads 124 and 127 are secured upon horizontally aligned looper-actuating shaft-sections 128 and 129, of which the main section 128 is journaled at one end in a bearing-lug 131 depending from the bed-plate 1. Adjacent to its other end the shaft-section 128 is journaled in a bushing 132 fixed in a frame-lug 133, and secured upon the end of said shaft-section is a bevel-gear 134 in mesh with a bevel-gear 135 upon the lower end of a vertically disposed intermediate shaft 136. The shaft 136 is journaled in suitable bearings within the bracket-arm standard 2 and at its upper end has a bevel-gear 137 driven by a bevel-gear 138 carried by the main-shaft 5. The shaft-section 129 is journaled in a specially constructed bearing-bushing 140 fixed in a frame-lug 141 and herein later referred to. The ends of the shaft-cranks 123 and 126 adjacent to the shaft-sections are offset from the axis of rotation of said shaft-sections to an equal extent and in the same direction, while the adjacent ends of said shaft-cranks converge toward a common point in the crank-dividing head 125 which is likewise offset from the axis of rotation of the shaft 128, 129. Consequently, the cranks 45 are not only inclined with respect to the axis of their shaft, but have a gyratory movement about said axis.

Embracing the shaft-crank 126 is a split sleeve 142, confined against endwise movements upon its crank by the crank-heads 125 and 127, to which sleeve 142 is secured a ball-socket carrier-plate 143 affording a journal for a ball 144 carried by a crank-arm 145 at the lower end of a vertically disposed looper-carrier rock-shaft 146. The rock-shaft 146 is journaled in a vertically-aper-tured rocking-sleeve 147 having intermediate its ends a boss 148 apertured transversely of the rock-shaft 146 to receive a fulcrum-pin 149 suitably secured in said boss. The fulcrum-pin 149 is pivotally mounted in spaced bearing apertures provided in a looper-bracket 150 secured, for adjustment crosswise of the line of seam formation, upon a frame-shelf 151 at the under side of the bed-plate 1. Upon the reduced upper end of the rock-shaft 146 is adjustably clamped an arm 152 socketed to receive the offset shank of the looper 107.

From the foregoing description of the looper-actuating mechanism, it will be understood that the blades of the loopers 106 and 107 are reciprocated endwise by the oscillating movements of the looper-carrying rock-shafts 112 and 146 about their longitudinal axes imparted by the respective shaft-cranks 123 and 126, and that said loopers are shifted sidewise by virtue of rocking

movements imparted to said rock-shafts about the axes of the fulcrum-pins 115 and 149. The endwise and sidewise movements of the loopers are so timed that the looper paths define elliptical fields, as illustrated in dotted lines in Fig. 30 of the drawings. These elliptical fields are substantially horizontal and are located entirely at the relatively remote sides of the needles 15 and 16, i. e., the looper movements are performed at the sides of the needles opposite to the piercer sides thereof, thereby providing for an abreast arrangement of the needles with an intermediate piercer.

In order to efficiently lubricate the sleeve-bearing surfaces of the shaft-cranks 123 and 126, said cranks are provided with longitudinal bores 153 and 154, which are preferably connected in the crank-dividing head 125 and are intersected at intervals by a plurality of radial apertures 155 in the shaft-cranks. The crank-bore 154 communicates with a bore 156 in the crank-head 127, which bore 156 opens into the shaft-aperture 127' in said head. Referring to Fig. 1, the bushing 140 is closed at its outer end by constructing it in cartridge form or by otherwise sealing its outer end, and the shaft-section 129 terminates short of said closed end of the bushing to provide a compression-chamber 140' within the bushing adjacent to the end of the shaft, which chamber opens into a bore 129' provided in the shaft-section 129 longitudinally thereof. The shaft-section 129 has in its bearing surface a spiral groove 157 arranged to progress toward the bushing-chamber 140' in the operation of the machine. The bushing 140 is provided with one or more lubricant-ducts communicating with a vertically disposed stand-pipe 158 which provides convenient means for supplying lubricant to the bearing surface of the shaft-section 129 from above the cloth-plate, it being understood that the usual slide-plates are employed adjacent to the throat-plate for access to the looper mechanism and that one of said slide-plates overlies the stand-pipe 158. Lubricant supplied to the stand-pipe 158 passes through the bushing ducts 120 to the shaft bearing surface of the bushing 140 and upon operation of the machine will be forcibly conducted by the spiral groove 157 to the compression-chamber 140'. Any lubricant thus applied to said chamber is forced through the shaft-bore 129' into the crank-head bore 156 and thence into the crank-bores 154 and 153, from which it passes through the radial ducts 155 to the bearing surfaces of the shaft-cranks 123 and 126. An additional stand-pipe 159 is preferably provided in the frame-shelf 117 to supply lubricant to the bearing in the lug 131 of the shaft-section 128.

Loop-spreaders and needle-guides

135

Disposed directly in front of the needles for cooperation with the loopers are a pair of loop-spreading fangs 160 and 161, supported for rocking movements about a substantially horizontal axis in paths intersecting the looper-fields of movement in a direction substantially normal to said fields, the paths of movement of said fangs being in substantially tangential relation with the paths of the respective needles. These fangs, which are lengthwise of arcuate form and have a common shank 162, have adjacent edges defining therebetween a slot 163 for receiving the inner or adjacent limbs of thread-loops presented by the loopers. The adjacent portions of the fangs which define the slot 163 merge, toward the free

150

ends of the fangs, into divergently inclined loop-spreading edges terminating in the substantially parallel and straight outer edges of the fangs to provide loop-seizing points. The fangs have 5 grooved or concave upper faces 166 and 167, affording clearance for the needles in the down strokes of the latter and insuring entrance of the needles into the thread-loops retained and spread by said fangs, said grooves being wide 10 enough, between the side walls thereof, to receive the needles on both their narrowly and widely spaced down strokes.

The shank 162 of the fangs is adjustably secured by a screw 168 upon a fang-carrying and 15 needle-guiding head 169 which is slotted below the fangs to provide spaced lugs 170 and 171 of which the opposed inner faces 172 and 173 are beveled or inclined in a downwardly approaching direction to serve as guides for the descending needles and as guards for preventing undue deflection of the needles into the paths of the loopers. Projecting from the needle-guiding head 169, substantially centrally between the lugs 170, 171 and between the paths of the needles in 20 the direction of seam formation, is a wedge-shaped fin 174 of downwardly increasing width, said fin having its upper or sharper edge extending into close proximity to the entrance to the fang slot 163. The fin 174 serves as a guard preventing interference with each other of the adjacent limbs of the needle-thread loops and insuring that said needle-thread loops are bowed on the looper sides of the needles. In addition, the 25 fin 174 by its wedge-shaped form prevents any lagging of the usual lateral movements of the needles while in the work in hemstitching machines, and in combination with the needle-guiding faces of the lugs 170, 171 positively insures the proper positions of the needles with respect 30 to their cooperating loopers.

The needle-guiding and fang-carrying head 169 has a shank 175 extending laterally therefrom and detachably secured upon a crank-member 176 of a horizontal rock-shaft 177 disposed substantially transverse to the direction of feed, said 45 crank-member being suitably recessed to provide clearance for the carrier of the looper 106. The rock-shaft 177 is journaled in spaced bearing-brackets 178 and 179 suitably secured upon the 50 looper-bracket 116, said rock-shaft carrying a forked crank-arm 180 connected by a link 181 with an upwardly inclined arm 182, which in the present case is shown as detachably secured upon its hub 183 pivotally mounted upon a fulcrum-shaft 184 rigidly projecting from the frame-lug 131. At its free end, the fulcrum-shaft 184 carries a well 185 packed with wicking for supplying lubricant through a longitudinal bore in said shaft and through bore-intersecting radial apertures to the bearing surface of the shaft. A tube 186 fixed in an aperture in the bed-plate above the well 185 provides convenient means for supplying lubricant to the wicking in the well. Projecting from the hub 183 is a fork 187 straddling 55 a three cornered cam 188 suitably secured upon the looper-actuating shaft-section 128, said cam actuating the rock-shaft 177 and providing for a short dwell at the direction reversing points of rocking movement of the shaft.

Looper-thread guides

The upper face of the bed- or cloth-plate 1 is provided with a pair of adjacent thread-receiving grooves 189 terminating at one end in a slot or recess 190 in the upper face of the cloth-plate 75

1 adjacent to the rearward side of the standard 2. The other ends of the grooves each terminate in a recess 191 connected by a transverse groove 192 with the usual cloth-plate opening 193 provided for the feeding and looper mechanism. The edge of the cloth-plate opening 193 where it is intersected by the groove 192 is rounded to serve as a guide for a looper-thread L. Disposed in the recess 191 is a grooved thread-guiding roller 194 rotatable upon a vertically directed spindle 195 of which one end is seated in the machine bed-plate and its other end in an aperture in a recess cover-plate 196. The cover-plate 196 is suitably secured in said recess 191 and has a finger 197 overlying the end of the cloth-plate thread-groove, 80 the free end of the finger 197 being slightly upturned to facilitate introduction of the looper-thread under said finger and about the roller into the cloth-plate opening 193.

Secured in a lug 198 of the looper-actuating 85 crank-sleeve 122 is the vertically directed stem of a take-up rod 199 bent forwardly and then laterally, about which rod the thread is led from the groove 192 to the looper. Only one looper-thread take-up is illustrated in the drawings, as only one 100 thread-carrying looper is employed in the present machine, but it will be understood that the lug 198 of the crank-sleeve 142 can be similarly provided with a take-up rod, when employing two 105 thread-carrying loopers, or that the take-up may be omitted from both crank-sleeves when using two non-thread carrying loopers.

Fulcrumed upon the bracket-arm standard at the rear side thereof is a two-armed lever 200, of which one arm carries at its free end a pair of 110 self-threading wire-loops 201 and is yieldingly held in the cloth-plate recess 190 by a spring 202. To introduce the looper-thread L into one or both of the cloth-plate thread-grooves 189, it is only necessary to manipulate the lever 200 to expose 115 the guide-loops 201 for threading purposes, and then to release the lever after the proper guide-loop or loops have been threaded.

Automatic presser-foot lifter

Upon the forward end of the rock-shaft 35 is secured an upwardly directed arm 203 having at its free end a horizontally apertured boss 204 projecting into an aperture in the bracket-arm 3. Slidingly disposed in said boss 204 is a spring-pressed plunger 205 normally urged out of engagement with a cam-nose 206 provided upon a side face of the spur-gear 40, the usual or any suitable means being provided for latching said plunger in cam-nose engaging position. Secured 130 upon the rearward end of the rock-shaft 35 is an arm 207 connected by a link 208 with the usual presser-foot lifter-lever 209, fulcrumed upon the rear side of the bracket-arm 3, whereby the presser-foot is intermittently lifted in the operating position of the plunger 205, to provide for more conveniently turning the work.

Looper-thread controlling mechanism

Clamped upon a suitable boss upon the stand- 140 ard 2 is a tension-bracket 211 carrying thread-tension devices 212 of any usual or suitable construction and including tension-releasing pins 213. Secured by a screw 214 for movement with the rock-shaft arm 207 and journaled upon the 145 hub of said arm is a tension-releasing arm 215 shaped to have its free end disposed between the tension-bracket and the arm-standard to engage the pins 213 and release the tensions upon manual operation of the presser-foot lifter 209.

The rear side of the bracket-arm is formed with the usual boss 216 having an opening affording access to the mechanism within the bracket-arm, and in the present machine said boss is provided with a bearing for an extension of the piercer rock-shaft 48. Clamped upon said rock-shaft, within the boss 216, is a rock-arm 217 from a side face of which projects a lug 218 apertured to fixedly receive a thread pull-off rod 219. The pull-off rod 219 is disposed adjacent to an ear 220 having thread-guiding apertures 221, said ear being offset laterally from its shank 222, which is secured by a screw 223 upon a nipper-supporting plate 224 suitably fixed upon the boss 216. 10
 15 Mounted upon said plate, adjacent to the pull-off rod 219, is a spring-pressed thread-nipper 226 of any usual or suitable construction and including a nipper-releasing pin 227. Fulcrumed upon a pivot-bolt 228 upon the supporting-plate 224 is a carrier-arm 229 having an offset lug 230 engageable by a nose 231 of a plate adjustably secured by screws 232 upon the presser-lifter link 208. The carrier-arm 229 has a stud-pin 233 projecting through an arcuate slot 224' in the supporting-plate 224, which pin is acted upon by a spring 234 housed in a socketed lug 235 of said supporting-plate to normally swing the lug 230 end of the carrier-arm upwardly to an extent limited by the upper end of said arcuate slot 224'. Suitably 20
 25 secured upon the carrier-arm 229 is the flat spring-shank of an upwardly directed wedge-arm 236 of which the inner face, adjacent to its free end, is stepped to provide an inclined shoulder 237. The wedge-arm is interposed between the inner end of the nipper-releasing pin 227 and the rock-arm 217 which has stepped cam-faces 238 and 239 in its free end.

During the operation of the machine, the free end of the wedge-arm 236 is positioned to be 40 engaged by the deeper cam-face 238 which rocks across the wedge-arm inclined shoulder 237; thereby intermittently flexing said arm and reciprocating the nipper-pin 227 endwise to alternately nip and release the thread. The looper-45 thread L is led from its supply, through a thread-guiding aperture 221, over the pull-off rod 219, through the nipper 226 to one of the tension devices 212 and thence to the lever guide-loop 201. The nipper release occurs during the downward 50 movement of the rock-arm 217, at which time the pull-off rod 219 is moving away from the thread led thereover, but as the thread is again nipped during the beginning of the upstroke of the rock-arm 217, the rod 219 engages and pulls 55 off thread from its supply.

When the lifter lever 209 is manually actuated to raise the presser-foot for insertion or removal of work, the nose 231 carried by the lifter-link engages the carrier-arm lug 230 to force the 60 wedge-arm 236 between the rock-arm cam-face 239 and the nipper-releasing pin 227, thereby releasing the nipper. At the same time, the tension-releasing arm 215 is actuated to engage the releasing pins of the tension devices. It is to be 65 understood, however, that there is sufficient lost-motion clearance between the lifter-link nose 231 and the carrier-arm lug 230 to maintain the carrier-arm 229 stationary during the operation of the machine. Likewise, the presser-lifting movements imparted by the rock-shaft 35 are insufficient to effect release of the tensions 212.

Needle-thread controller mechanism

Secured upon the bearing-lug bushing 50, 75 which affords a bearing for the piercer rock-shaft

48, is the bossed lower end of a tension-and-nipper bracket 240 having an overhanging shelf 241 upon which are mounted any usual or suitable thread-tensions 242 and a thread-nipper 243, including tension-releasing pins 244 and a nipper-releasing pin 245 extending below said shelf 241. Engageable with said pins is a releasing-arm 246 suitably guided for vertical movements upon the bracket 240. Depending from the releasing-arm 246 is a rod 247 of which the laterally bent lower end overlies the presser-foot lifter 209, whereby the tensions and nipper are released upon operation of said lifter 209 to raise the presser-foot. Abutting the lower end of the nipper-releasing pin 245 is an auxiliary pin 248 which extends through a vertical aperture in the arm 246 for engagement by a cam-lug 53' provided upon the upper face of the crank-arm 53 which actuates the piercer rock-shaft, whereby the nipper 243 is automatically released during a part of each stitch-forming cycle. Carried by the crank-arm 53 is a thread pull-off rod 249 vibrated in a path between the nipper and a suitably apertured thread-guiding arm 250 to which the needle-threads N are led from their supply, 100 it being understood that the rod 249 acts to pull thread from its supply at a time when the nipper is closed.

The bracket-arm head 4 is provided with an apertured boss 251 in which is suitably secured a stud 252 having a flanged free end carrying a bracket-plate 253. A portion of the boss-aperture for the stud 252 is enlarged to provide an annular recess receiving a sleeve 254 having a peripherally knurled flange or adjusting nut 255, 105 said sleeve being secured for circular adjustment by a set-screw 256. Surrounding the stud 252, between the nut 255 and the flanged end of said stud, is a coil-spring 257 of which one end is anchored in an aperture in the nut and the other 110 or free end extends upwardly adjacent said plate and is reversely bent to provide a thread-engaging hook 258. Disposed in engagement with the side face of the bracket-plate opposite to the spring 257 side thereof is another sleeve 259 having at its outer end a flange providing a nut 260, said sleeve being adjustably secured against the bracket-plate by a screw 261 embraced by the sleeve and threaded into the end of the stud 252. Surrounding the sleeve 259 is a coil-spring 115 262 having one end anchored in the nut 260 and its other or free end extending upwardly adjacent the bracket-plate 253 and reversely bent to provide a thread-engaging hook 263. The upper end of the bracket-plate has its opposite 120 faces ribbed to provide guideways 264 extending transversely of the stud 252, said guideways being interrupted intermediate their ends to provide clearance gaps for the upwardly extending slack-thread controller springs described. Ad- 125 justably slidable in said guideways are spaced ribs 266 and 267 provided upon the inner faces of retainer-blocks 268, which latter are secured by a single screw 269 passing through an elongated slot 253' in the bracket-plate 252. The 130 ribs 267 of said blocks serve to adjustably limit yielding movement of the springs in a direction responsive to the pull of the threads N, while movement of said springs in the opposite direction is limited by the opposed gap-defining ends 135 of the bracket-plate guideway 264 and the guide-ribs 266. Suitably secured upon the bracket-plate 253 is the shank of a guide-loop 270 receiving the needle-threads N from the tensions 242, the threads being then each passed into a spring 140 145 150

hook 258 or 263 and thence forwardly to a take-up mechanism about to be described. It will be understood that the springs 258, 263 have the usual function of controlling the thread slack during the operation of the machine, that the tensions of the springs may be individually adjusted by means of the nuts 255 and 260, and that the spring-hooks have an adjustable range of movement provided by the blocks 268.

10 The needle-bar link 9 has intermediate its ends a substantially horizontal recessed seat 271 in which is secured by a screw 272, one member of a U-shaped take-up holder 273 extending about the rear side of the needle-bar 11. The 15 upwardly directed other member of said holder 273 is ribbed to provide a seat for the correspondingly grooved lower end of a take-up arm 274, secured upon the holder by screws 275. The offset free end of the arm 274 has an enlarged 20 thread-opening 276, one of the opening-defining walls having an inclined threading slit 277. Suitably secured upon the needle-bar collar 10 to extend upwardly at opposite sides of the take-up arm 274 are the stems of self-threading thread-guides 278 and 279, which accordingly are reciprocated vertically with the needle-bar, while the thread-receiving end of the take-up arm has an elliptical path of movement in a vertical plane between said thread-guides and across a line connecting said guides. The needle-threads N are led through the thread-guide 278 from the slack-thread controller springs 258, 263, and are then threaded into the take-up arm opening 276 and into the thread-guide 279, from which the 30 threads are passed through suitable fixed guides to the respective needles. The large thread-opening 276 affords a dwell in the action upon the thread by the take-up arm 274, as the latter passes from one side to the other of the line connecting the thread-guides 278 and 279.

Operation

In the operation of the machine, the piercer 43 commences its descending movements before 45 the needles have quite completed their upstroke, said piercer reaching the lower end of its relatively shorter stroke at about the time the needles are entering the work. Following immediately upon advance of the work by the feed-dog 59, 50 the needles penetrate the work in their closely spaced relationship, i. e., the needles enter the aperture produced in the work by the piercer. While the needles are in the work, they are moved slightly sidewise in directions away from 55 each other crosswise of the line of seam formation. Should the needles lag in this sidewise movement thereof, the wedge-shaped fin 174 of the looper mechanism, which fin is at this time swinging upwardly, insures the lateral movement 60 of the needles into proper position thereof for seizure of the needle-thread loops N¹, N² by the loopers.

The loopers 106 and 107 begin their endwise 65 advancing movements in a substantially horizontal plane at about the time the needles are entering the work, and reach their loop-seizing position, illustrated in Figs. 21, 22 and 23 of the drawings, directly after the needles commence 70 their upstroke. At this time, the piercer 43 has emerged from the work in its upstroke and the loop-detaining and spreading fangs 160, 161 are pausing in their retracted position with the fin 174 disposed between the needles, whereby the 75 needle-thread loops are prevented from inter-

ferring with each other and are bowed outwardly on the looper sides of the needles.

In Figs. 24, 25 and 26 of the drawings, the loopers have advanced to their extreme forward limit of movement and have been shifted slightly sidewise to provide clearance for the fangs 160, 161, which at this time begin their advancing movement. It will be observed that the blade of the thread-carrying looper 106 has entered and is detaining the needle-thread loop N¹, and that the looper-thread loop L¹ is opened by the lateral movement of said looper 106 for entrance by the fang 161. However, the needle-thread loop N² has been entered by merely the point of the looper 107, being detained by the spur 107' of said looper and thereby carried forward into position for entrance by the fang 160, the slight sidewise movement of the looper 107 serving to open the loop N² and to provide the necessary clearance for the fang 160.

In the positions of the parts illustrated in Figs. 27, 28 and 29 of the drawings, the fangs 160, 161 are about midway of their advancing movement into the loops N², L¹, the inner or adjacent limbs of said loops entering the fang-slot 163 whereby said loops are held spread as illustrated more particularly in Fig. 29. As the fangs 160 and 161 reach their extreme advanced position, illustrated in Figs. 30, 31 and 32 of the drawings, the loopers 106 and 107 are on the point of shedding the needle-thread loops N¹, N², with the needle-loop N¹ embracing the looper-thread L, the needle-loop N² detained by the fang 160 and the looper-loop L¹ detained by the fang 161.

It will be observed that the feed-dog 59, after the work-advancing movement thereof before referred to and during the described operation of the looper mechanism is gradually returning in its lowered position but so slowly as to leave open the front ends of the throat-plate slots 82, thereby providing the necessary thread-loop clearance.

The piercer begins its succeeding work-penetrating movement at about the time the loopers begin their retracting movement, and the needles reach the top of their stroke when the fangs 160, 161 have completed their advancing movement, said needles being shifted still further apart as they approach the upper end of their stroke. The fangs now pause or dwell in their advanced position until the needles in their more widely spaced relationship are about to penetrate the work, at which time the fangs begin their retracting movement. As illustrated in Figs. 33 to 36, inclusive, the descending needles enter the fang-grooves 166, 167, which are wide enough to accommodate the needles when widely or narrowly spaced, the needles thus entering the thread-loops L¹, N² detained and spread by the fangs. As the needles continue their descending movements, the fangs back out of the loops detained thereby, thereby bringing the wedge-shaped fin into operative position with respect to the needles for the purpose previously described, said fangs pausing or dwelling for an appreciable period in their retracted position. As the needles approach the lower end of their stroke, they are vibrated slightly sidewise in a direction toward each other into loop-taking position. This sidewise approaching movement of the needles is insured by the inclined faces 172, 173 of the guide-lugs 170, 171, should the needles tend to lag. The loop seizing and spreading operations are then repeated while the needles

are rising and vibrated toward each other into narrowly spaced relationship and then again descend for cooperation with the loopers. During all this time the feed-dog 59 has been slowly returning below the upper surface of the throat-plate to its initial position, said feed-dog rising with the succeeding ascending movement of the needles preparatory to again feeding the work and at the completion of the three-stitch hem-stitch figure.

In Fig. 39 of the drawings, another non-thread carrying looper 107 is substituted for the thread-carrying looper 106 described, while in Fig. 40 another thread-carrying looper 106 is substituted for the described looper 107, it being understood from the foregoing description that the looper mechanism functions equally effectively whether thread-carrying or non-thread-carrying loopers are employed and that the loop-conciliation is definite and certain.

Having thus set forth the nature of the invention, what I claim herein is:—

1. In a sewing machine, an endwise reciprocating thread-carrying needle, a looper cooperating with said needle having an arcuate path of needle-thread loop seizing movement about an axis substantially parallel with the path of reciprocation of said needle, a loop-detainer adapted to enter the needle-thread loops seized by said looper and to spread said loops in position for entrance by said needle, and means for actuating said looper and loop-detainer.

2. In a sewing machine, an endwise reciprocating thread-carrying needle, a looper cooperating with said needle having an arcuate path of needle-thread loop seizing movement about an axis substantially parallel with the path of reciprocation of said needle, a loop-detainer having an arcuate path of movement about an axis substantially transverse to said axis of looper movement adapted to seize thread-loops presented by said looper and to spread the loops seized thereby for entrance by said needle, and means for actuating said looper and loop-detainer.

3. In a sewing machine, an endwise reciprocating thread-carrying needle, work-feeding mechanism, a needle-thread loop seizing looper, a loop-detainer having an arcuate path of movement about an axis substantially transverse to the direction of feed adapted to seize thread-loops from said looper and to spread said loops in position for entrance by said needle, and means for actuating said looper and loop-detainer.

4. In a sewing machine, an endwise reciprocating thread-carrying needle, a needle-thread loop seizing looper having endwise and sidewise movements in a path defining a field entirely at one side of the needle-path of reciprocation, means for actuating said looper, and means cooperating with said looper adapted to seize a thread-loop presented by said looper and to detain said looper-presented loop in position for entrance by said needle.

5. In a sewing machine, a vertically reciprocating thread-carrying needle, a needle-thread loop-seizing looper having endwise and sidewise movements in a path defining a substantially horizontal field, a loop-detainer having a path of movement intersecting said field in a direction substantially normal thereto, and means for actuating said looper and loop-detainer.

6. In a sewing machine, an endwise reciprocating thread-carrying needle, a needle-thread loop seizing looper having endwise and sidewise

movements in a path defining a field entirely at one side of the needle-path of reciprocation, a loop-detainer cooperating with said looper having a path of movement intersecting said field, and means for actuating said looper and loop-detainer.

7. In a sewing machine, an endwise reciprocating thread-carrying needle, a thread-carrying looper cooperating with said needle in the seizure of thread-loops therefrom having endwise and sidewise movements in a path defining a field entirely at one side of the needle-path of reciprocation, a loop-detainer cooperating with said looper in the seizure of looper-thread loops therefrom and cooperating with said needle in the presentation of the seized looper-thread loops thereto, and means for actuating said looper and loop-detainer.

8. In a sewing machine, an endwise reciprocating thread-carrying needle, a needle-thread loop seizing looper having endwise and sidewise movements in a path defining a field entirely at one side of the needle-path of reciprocation, said looper having a loop-entering point and a loop-arresting spur, a loop-detainer cooperating with said looper in the seizure of the needle-thread loops therefrom and adapted to present said loops for entrance by the needle, and means for actuating said looper and loop-detainer.

9. In a sewing machine, a pair of endwise reciprocating thread-carrying needles, and mechanism complemental to said needles in the formation of chain-stitches including a pair of loopers having endwise and sidewise movements in paths defining fields located wholly at the relatively remote sides of said needle-paths of reciprocation.

10. In a sewing machine, a pair of endwise reciprocating thread-carrying needles, a pair of loopers having needle-thread loop-seizing movements at the relatively remote sides of said needles, means for actuating said loopers, a pair of loop-detaining fangs adapted to seize thread-loops from said loopers and to spread the looper-presented loops for entrance by said needles, and means for actuating said fangs.

11. In a sewing machine, work-feeding mechanism, a pair of endwise reciprocating thread-carrying needles arranged abreast with respect to the direction of feed, a pair of loopers having endwise loop-seizing movements at the relatively remote sides of said needles and sidewise looper-separating and approaching movements, means for actuating said loopers, and loop-detaining means complemental to said needles and loopers in the formation of chain-stitches.

12. In a sewing machine, a pair of endwise reciprocating thread-carrying needles, a pair of loopers cooperating with said needles in the seizure of thread-loops therefrom having sidewise looper-separating movements, means for actuating said loopers, a pair of loop-detainers having operative paths of movement between said loopers in the seizure of thread-loops therefrom, and means for actuating said detainers.

13. In a sewing machine, work-feeding mechanism, a pair of endwise reciprocating thread-carrying needles arranged abreast with respect to the direction of feed, a pair of loopers cooperating with said needles in the seizure of thread-loops therefrom having endwise and sidewise movements in paths defining fields at the relatively remote sides of said needles, means for actuating said loopers, a pair of loop-detainers cooperating with said loopers having paths of

- movement intersecting said fields, and means for actuating said loop-detainers. 80
14. In a sewing machine, work-feeding mechanism, a pair of endwise reciprocatory thread-carrying needles arranged abreast with respect to the direction of feed, a pair of loopers having needle-thread loop-seizing movements opposed to the direction of feed, means for actuating said loopers, a pair of loop-detainers cooperating with 85 said loopers in front of the needles with respect to the direction of feed, and means for actuating said loop-detainers.
15. In a sewing machine, work-feeding mechanism, a pair of endwise reciprocatory thread-carrying needles, a pair of loopers cooperating with said needles having endwise loop-seizing movements in arcuate paths about axes substantially parallel with the needle-paths of reciprocation, said looper axes being disposed at opposite 90 sides of the line of feed, means for actuating said loopers, and loop-detaining means complementary to said needles and loopers in the formation of chain-stitches. 95
16. In a sewing machine, a pair of endwise reciprocatory and laterally vibratory thread-carrying needles, needle-actuating mechanism including means for vibrating said needles laterally in directions toward and from each other, and mechanism complementary to said needles 100 in the formation of chain-stitches including a pair of loopers cooperating with the respective needles at the relatively remote sides thereof in the seizure of needle-thread loops. 105
17. In a sewing machine, work-feeding mechanism, a pair of endwise reciprocatory and laterally vibratory thread-carrying needles arranged abreast with respect to the direction of feed, a reciprocatory work-penetrating piercer between the needles, and mechanism complementary to said needles in the formation of chain-stitches, including a pair of loopers having needle-thread loop-seizing paths of movement at the sides of said needles opposite to the piercer sides thereof. 110
18. In a sewing machine, work-feeding mechanism, a pair of endwise reciprocatory and laterally vibratory needles arranged abreast with respect to the direction of feed, needle-actuating mechanism including means for vibrating said needles laterally in directions toward and from each other, and mechanism complementary to said needles in the formation of chain-stitches including a pair of loopers having fixed paths of movement in directions to seize the needle-thread 115 loops. 120
19. In a sewing machine, work-feeding mechanism, a pair of endwise-reciprocatory and laterally-vibratory needles arranged abreast with respect to the direction of feed, needle-actuating mechanism including means for vibrating said needles relatively laterally to perform narrowly and more widely spaced work-penetrating movements, a reciprocatory work-penetrating piercer between the needles, a pair of loopers having 125 needle-thread loop-seizing movements at the sides of the needles opposite to the piercer sides thereof, means for actuating said loopers, and means for seizing thread-loops presented by said loopers and for positioning the looper-presented 130 loops for entrance by said needles in both the narrowly and more widely spaced work-penetrating movements of the needles. 135
20. In a sewing machine, a pair of endwise-reciprocatory thread-carrying needles, and mechanism complementary to said needles in the for- 140
- mation of chain-stitches including a pair of loopers having arcuate paths of needle-thread loop-seizing movements at the relatively remote sides of said needles and about axes substantially parallel with the paths of needle reciprocation. 145
21. In a sewing machine, a work-support, work-feeding mechanism, an endwise-reciprocatory and laterally-vibratory needle, needle-actuating mechanism including means for vibrating said needle crosswise of the line of feed, and mechanism complementary to said needle in the formation of chain-stitches including a looper having a fixed needle-thread loop seizing path of movement defining a field substantially parallel with the work-support. 150
22. In a sewing machine, an endwise reciprocatory thread-carrying needle, a needle-thread loop-seizing looper, means for actuating said looper, a loop-detainer having an arcuate path of movement in substantially tangential relation with the needle-path of reciprocation and about an axis transverse to said needle-path, and means for actuating said loop-detainer in timed relation to seize thread-loops from said looper and to present the same for entrance by said needle. 100
23. In a sewing machine, work-feeding mechanism, a vertically reciprocatory thread-carrying needle, a needle-thread loop-seizing looper, means for actuating said looper, a loop-detainer having an arcuate path of movement in substantially tangential relation with the needle-path of reciprocation and about a substantially horizontal axis transverse to the direction of feed, and means for actuating said loop-detainer in timed relation to seize thread-loops from said looper and to present the same for entrance by said needle. 105
24. In a sewing machine, an endwise reciprocatory thread-carrying needle, a needle-thread loop-seizing looper, means for actuating said looper, a loop-detainer having an arcuate path of movement in substantially tangential relation with the needle-path of reciprocation and about an axis transverse to said needle-path, said loop-detainer having lengthwise thereof a needle-receiving groove, and means for actuating said loop-detainer in timed relation to seize thread-loops from said looper and to present the same for entrance by said needle. 110
25. In a sewing machine, an endwise reciprocatory thread-carrying needle, a looper cooperating with said needle having endwise loop-seizing movements in an arcuate path about an axis substantially parallel with the needle-path of reciprocation, means for actuating said looper, a loop-detainer having an arcuate path of movement in substantially tangential relation with the needle-path of reciprocation about an axis transverse to said needle-path, said loop-detainer having lengthwise thereof a needle-receiving groove, and means for actuating said loop-detainer in timed relation to seize thread-loops from said looper and to present the same for entrance by said needle. 115
26. In a sewing machine, work-feeding mechanism, an endwise reciprocatory and laterally vibratory thread-carrying needle, means for imparting to said needle work-penetrating movements in paths spaced crosswise of the line of feed, a needle-thread loop-seizing looper, means for actuating said looper, a loop-detainer having an arcuate path of movement in substantially tangential relation with the path of needle reciprocation, said loop-detainer having lengthwise thereof a groove adapted to receive the needle in its spaced paths of reciprocation, and means for 120

- actuating said loop-detainer in timed relation to seize thread-loops from said looper and present the same to said needle.
27. In a sewing machine, a pair of endwise reciprocatory thread-carrying needles, a pair of loopers cooperating with said needles in the seizure of thread-loops therefrom, means for actuating said loopers, a pair of loop-detaining fangs cooperating with said loopers having therebetween a thread-receiving slot terminating in a shank common to both fangs, and means for actuating said fangs in arcuate paths substantially tangential to the needle-paths of reciprocation about an axis transverse to said needle-path. 80
- 10 28. In a sewing machine, work-feeding mechanism, a pair of endwise reciprocatory and laterally vibratory needles arranged abreast with respect to the direction of feed, needle-actuating mechanism including means for vibrating said needles in directions toward and from each other to perform narrowly and more widely spaced work-penetrating movements, a work-penetrating piercer reciprocatory in a path between the needles, a pair of loopers having needle-thread 90
- 20 loop-seizing paths of movement at the sides of said needles opposite to the piercer sides thereof, means for actuating said loopers, a pair of adjacent loop-detainers having arcuate paths of movement intersecting the looper paths in substantially tangential relation with the needles, said loop-detainers having lengthwise thereof grooves entered by the needles in their spaced paths of reciprocation, and means for actuating said loop-detainers. 95
- 25 29. In a sewing machine, the combination with an endwise reciprocatory needle, of mechanism complementary to said needle in the formation of chain-strokes, including a looper supported for endwise needle-thread loop-seizing movements in an arcuate path about an axis substantially parallel with the path of needle reciprocation and for sidewise movements about an axis transverse to said endwise movement axis, a rotary actuating shaft having a gyroscopic inclined crank, and operative connections between said crank and the looper-supporting means for imparting both the endwise and sidewise movements to said looper. 100
- 30 30. In a sewing machine, the combination with a vertically reciprocatory needle, of mechanism complementary to said needle in the formation of chain-strokes, including a needle-thread loop-seizing looper, a vertically disposed rock-shaft carrying said looper, a rocking member providing a bearing for said rock-shaft supported for pivotal movements about a substantially horizontal axis, and means for rocking said shaft about its longitudinal axis and for rocking said member upon its support. 105
- 35 31. In a sewing machine, the combination with a vertically reciprocatory needle, of mechanism complementary to said needle in the formation of chain-strokes, including a needle-thread loop-seizing looper, a vertically disposed rock-shaft carrying said looper, a rocking member providing a bearing for said rock-shaft supported for pivotal movements about a substantially horizontal axis, a rotary shaft having a gyroscopic inclined crank, and operative connections with said inclined crank for actuating said rock-shaft about its longitudinal axis and for rocking said member upon its support to thereby impart endwise and sidewise movements to said looper. 110
- 40 32. In a sewing machine, the combination with a vertically reciprocatory needle, of mechanism complementary to said needle in the formation of chain-strokes, including a needle-thread loop-seizing looper, a vertically disposed rock-shaft carrying said looper, a rocking member providing a bearing for said rock-shaft supported for pivotal movements about a substantially horizontal axis, a rotary shaft having a gyroscopic inclined crank, a sleeve embracing said inclined crank, operative connections between said sleeve and the looper-carrier for actuating said looper, and a looper-thread take-up member carried by said sleeve. 115
- 45 33. In a sewing machine, the combination with a pair of vertically reciprocatory needles, of mechanism complementary to said needles in the formation of chain-strokes, including a pair of needle-thread loop-seizing loopers, a pair of looper-carriers, a rotary shaft having a pair of gyroscopic inclined cranks offset at their opposite ends from the axis of rotation of said shaft, and operative connections between said inclined cranks and said looper-carriers adapted to transmit endwise and sidewise movements to said loopers. 120
- 50 34. In a sewing machine, the combination with a pair of vertically reciprocatory needles, of mechanism complementary to said needles in the formation of chain-strokes, including a pair of needle-thread loop-seizing loopers, a pair of looper-carriers, a rotary shaft having a pair of oppositely inclined gyroscopic cranks arranged in end-to-end relationship upon the shaft, and operative connections between said inclined cranks and said looper-carriers adapted to transmit endwise and sidewise movements to said loopers. 125
- 55 35. In a sewing machine, a work-support, work-feeding mechanism, a pair of vertically reciprocatory thread-carrying needles arranged abreast with respect to the direction of feed, a pair of loopers cooperating with said needles below the work-support in the seizure of needle-thread loops, means for actuating said loopers, a needle-guiding head disposed below the work-support having downwardly converging opposed needle-guiding faces and having a wedge-shaped needle-separating fin of downwardly increasing width intermediate said needle-guiding faces, and means for rocking said needle-guiding head in differentially timed relationship with respect to said loopers. 130
- 60 36. In a sewing machine, a vertically reciprocatory thread-carrying needle, mechanism complementary to said needle in the formation of chain-strokes including a thread-carrying looper cooperating with said needle in the seizure of thread-loops therefrom, a looper-carrier, a rotary actuating shaft having a gyroscopic inclined crank, a sleeve embracing said inclined crank, operative connections between said sleeve and the looper-carrier for actuating said looper, and a looper-thread take-up member carried by said sleeve. 135
- 65 37. In a hemstitching machine, work-feeding mechanism, a pair of endwise reciprocatory and laterally vibratory needles, a reciprocatory work-penetrating piercer, a thread-carrying looper cooperating with one of said needles in the formation of double-thread chain-strokes, a non-thread carrying looper cooperating with the other needle in the formation of single-thread chain-strokes, and means for actuating said loopers. 140
- 70 38. In a hemstitching machine, work-feeding mechanism, a pair of endwise reciprocatory and laterally vibratory needles arranged abreast with respect to the direction of feed, needle-actuating mechanism including means for vibrating 145
- 75 150

- 5 said needles in directions toward and from each other to perform narrowly and more widely spaced work-penetrating movements, a work-penetrating piercer reciprocatory in a path between the needles, a thread-carrying looper co-operating with one of said needles in the seizure of thread-loops therefrom, means for seizing and presenting loops of looper-thread for entrance by said needle, a non-thread carrying looper co-operating with the other needle in the seizure of thread-loops therefrom, and means for presenting for entrance by said other needle the needle-thread loops seized by the non-thread carrying looper. 80
- 10 39. In a hemstitching machine, a pair of endwise reciprocatory and laterally vibratory needles, needle-actuating mechanism including means for vibrating said needles in directions toward and from each other to perform narrowly and more widely spaced work-penetrating movements, a piercer having a reciprocatory work-penetrating path of movement between the needles, mechanism complementary to said needles in the formation of two rows of single-thread chain-stitches, and mechanism for advancing the work a less number of times than the number of needle reciprocations. 85
- 15 40. In a sewing machine, a vertically reciprocatory and laterally vibratory needle, looper mechanism complementary to said needle in the formation of chain-stitches, a throat-plate provided with a needle-slot and with a feed-dog slot rearwardly of and opening into said needle-slot, a feed-dog operating in said feed-dog slot, means for imparting a less number of forward work-advancing movements to said feed-dog than the number of needle reciprocations and for retarding the return movements of said feed-dog to provide thread-chain clearance in said feed-dog slot. 90
- 20 41. In a sewing machine, a vertically reciprocatory and laterally vibratory needle, work-feeding mechanism, a throat-plate provided with a needle-slot transverse to the direction of feed and with a feed-dog slot disposed rearwardly of and opening into said needle-slot, said work-feeding mechanism including a feed-dog of which one end has a rising work-engaging movement within said needle-slot. 95
- 25 42. In a hemstitching machine, work-feeding mechanism, a pair of endwise reciprocatory and laterally vibratory needles arranged abreast with respect to the direction of feed, needle-actuating mechanism including means for vibrating said needles in directions toward and from each other to perform narrowly and more widely spaced work-penetrating movements, a work-penetrating piercer reciprocatory in a path between the needles, a throat-plate provided with a needle-and-piercer slot extending transversely of the direction of feed and with a pair of feed-dog slots disposed rearwardly of and opening into said needle-slot, said work-feeding mechanism including adjacent feed-dog members of which the front ends have a rising work-engaging movement within said needle-slot. 100
